UNITED STATES PATENT OFFICE.

HAROLD I. ACKER, OF NEW YORK, N. Y., ASSIGNOR TO FOAMITE FIREFOAM COMPANY, OF NEW YORK, N. Y., A CORPORATION OF DELAWARE.

DUPLEX HYDRANT.

1,388,785.

Specification of Letters Patent. Patented Aug. 23, 1921.

Application filed January 2, 1920. Serial No. 348,717.

To all whom it may concern:

Be it known that I, HAROLD I. ACKER, a citizen of the United States, and a resident of New York city, in the county of New

5 York and State of New York, have invented certain new and useful Improvements in Duplex Hydrants, of which the following is a specification.

My invention relates to fire extinguishers, 10 and in particular to apparatus for use in a system employing two separate solutions.

Systems of this type now in general use employ solutions which, when mixed, interact chemically to produce a suitable fire extinguishing medium, one common type forming a heavy lather-like foam. Such solutions must necessarily be kept out of contact with each other until immediately adjacent the point of application to a fire; and various 15 systems employing duplex conduits and provided with suitable mixing and projecting heads have been developed for use with this type of extinguishing medium.

In connection with systems of this type, 20 flexible hose lines have been invented, such as are disclosed in the patent to Meigs #1,319,101 and the patent to Walker #1,299-272, adapted to be connected to a suitable duplex source. The use of these hose lines 25 has proved extremely advantageous because of their great adaptability, as no fixed foam-producing installation is required, and the mixed solutions can be applied to a fire anywhere within a large area without other apparatus than suitable fixed supply lines and 30 the flexible hose connected thereto.

The arrangements for connecting the duplex hose to the source of supply have, however, been unsatisfactory. For efficient op-

40 eration of two-solution systems, it is necessary to mix the solution in definite proportions. The valves of the mixing apparatus and usually the conduits conveying the separate solutions, are suitably proportioned

45 with this end in view. Consequently, such a system loses some of its efficiency if the proportions are varied. This result is common with the present method of connecting the hose to the source of supply, as each so-

50 lution-carrying member of the duplex hose is connected separately and by independent means to the main line. Consequently, in order to turn the solutions into the hose, it has been necessary to turn each solution on 55 separately, almost necessarily producing an

improper mixture at first, and often permanently impairing the mixture by failure to open the connecting valve of one of the solutions to its fullest extent.

The primary object of my invention is to 60 provide apparatus for connecting a duplex distributing system, such as a hose line, with a duplex source of supply.

A further object is to provide a connecting device of this type which is adapted to insure proper proportional release of the two 65 solutions, so that a perfect intermixture at all times is assured.

In the specific embodiment of my invention, I provide a hydrant which is adapted 70 to be connected to dual main pipe lines, and which is provided with suitable means for rapidly connecting a duplex hose line. This construction permits the use of the two-solution system in a manner heretofore practicable only with water systems, by employing 75 main pipe lines extending through the general area to be protected and provided at suitably spaced points with hydrants. With this arrangement, a fire in any part of the 80 area can be rapidly attacked without a fixed system of sprinklers or other solution ejectors, and without the transportation of portable extinguishers. Furthermore, the supply 85 of the extinguishing solution is not limited by the capacity of such portable apparatus.

My invention, however, is not restricted to this specific use, although it is believed to be the first practical apparatus permitting the 90 use of such a system.

A further object of my invention is to provide means for releasing the two solutions, so constructed and arranged that the release will necessarily be simultaneous.

I also provide such a construction which 95 is simple and strong, positive in action, easy and rapid to manipulate, and in which the parts may readily be exposed for inspection or replacement.

I further provide an arrangement in which 100 the two solutions are effectively prevented from accidental contact with each other, and in which the danger of sticking through incrustation of parts is effectually avoided.

Other objects and advantages of my invention will be apparent from the following description, taken in connection with the accompanying drawing, which consists of a vertical cross-section through a preferred 105 form of hydrant.

The hydrant comprises a body portion 10 provided with two valve chambers 11 completely separated from each other, as by central partition 12, which preferably is 5 cast integral with the body 10. Each chamber 11 is connected with a main supply pipe 13 in any desired way. In the preferred form, I employ a base 14, which may be separate from body 10 and connected thereto 10 as by bolts 15, the base being suitably apertured to receive the threaded ends of pipes 13. The connection between pipes 13 and chambers 11 is closed by suitable valves of any desired type provided with spindles 16 15 passing upwardly through chambers 11 and controlling the operation of the valves. I have illustrated one form of valve construction, which includes a seat 17 preferably carried by base 14. The valve head 18 is 20 mounted on spindle 16, as by providing a lock nut 19 threaded into the top of the valve head 18 to hold the latter in engagement with a shoulder 20 on spindle 16. Valve head 18 is preferably provided with 25 a suitable seating plate or ring 21, which may be removably held in place to permit renewal thereof, as by nut 22 threaded on the lower end of spindle 16. It will be apparent that this specific form of valve construction, while very simple, strong and effective, is simply illustrative, and many other types of valve may be employed. It is to be noted, however, that the specific 30 construction disclosed provides a relatively narrow rim along the upper edge of seat 17 with which washer 21 is in contact, tending to prevent sticking or freezing of the valve through accumulation or incrustation of substances carried by the solutions.

40 While I prefer to employ a connection with the main supply pipes in which the connecting passages are located at the bottom of chambers 11 and substantially aligned therewith, permitting the valve heads 18 45 to be mounted rigidly on spindle 16 transverse to the chambers, it will be apparent that many other types of spindle actuated valves are well known and may be substituted for the type disclosed; the appropriate 50 changes in the connections with the main supply pipes being apparent to those skilled in the art.

I provide means for guiding spindles 16, which preferably includes bearings 23 at 55 the upper end of each chamber, adapted to permit free action of the spindle without allowing the solutions to flow past the bearings and out of the chambers 11. Bearings 23 preferably include bushings 24, and 60 when the spindles are longitudinally reciprocated, as in the preferred form disclosed, each is preferably provided with a sealing disk or plate 25 having an upper surface 26 either integral with or of separate material from the plate, and composed of rela-

tively soft material, such as lead, which when drawn upwardly against bushing 24 serves both to limit the motion of spindle 16 and to seal the bushing effectually against any possible leakage of solution 70 therethrough. I also may provide a guide or bearing 27 for each spindle adjacent the lower end thereof, which may be mounted on suitable extensions 28 on the walls of each chamber 11. 75

I provide means for simultaneously operating the valves by common control of spindles 16. The preferred form disclosed is adapted to raise and lower the spindles 16 simultaneously, and comprises a cross 80 head 29 connected to the upper end of each spindle, as by nuts 30, which permit accurate adjustment of the cross head on each spindle 16. Operating screw 31 is connected to the cross head 29 and, in the preferred 85 form disclosed, is rotatably mounted on said cross head, as by lock bushing 32 threaded into cross head 29 and serving as a journal in which the screw 31 revolves. Said screw 31 is threaded through a bushing 33 on the 90 hydrant head 34, which is carried by body 10 and preferably detachably mounted thereon, as by screws 35. Means for rotating screw 31 is provided, which may consist of a hand wheel 36 engaging a sleeve 37 95 through which screw 31 is threaded, lock nut 38 holding screw 31 in adjusted position in said sleeve.

While the specific form of valve shifting mechanism disclosed is adapted only to reciprocate the spindles 16, I do not consider my invention, in its broad aspect, as limited to this arrangement, as valves operated by 100 rotating spindles are well known.

Suitable outlets 39 from chambers 11 are 105 provided, preferably being of the well-known hydrant type having a threaded exterior shoulder 40 closed by screw cap 41.

The mode of operation of the hydrant will be apparent. The valves are necessarily 110 operated simultaneously, thus assuring simultaneous arrival of the two solutions at the mixing chamber. Furthermore, pipes 13 connecting with the main supply lines, and outlets 39, are suitably proportioned 115 so that the amount of solution passing therethrough must necessarily be exactly correct to produce a mixture of maximum efficiency. While chambers 11 may be similarly proportioned, I prefer to provide 120 means for filling the chambers at an equal rate, independent of the size of pipes 13, by suitably proportioning valve heads 18, so that the head closing the smaller pipe 13 will be spaced from the walls of its chamber 11 by a distance greater than the clearance of the other head, permitting a more rapid flow of the solution from the smaller pipe, at the left of the drawing, and a consequent even filling of chambers 11. How- 125 130

ever, this feature is not essential, as the difference in the time required to fill the two chambers 11 is relatively slight.

It will be apparent that my hydrant is 5 so constructed as to be readily and cheaply manufactured, adjustable throughout, and so arranged that any part thereof may be readily and rapidly removed and replaced. It is, furthermore, arranged so that the 10 working parts are provided complete protection by a heavy casing, but are readily and rapidly accessible for inspection, without interfering with the adjustment of the working parts, the valves being exposed by 15 removing bolts 15, and the cross head connection by removing screws 35.

While I have described the preferred form of my invention and indicated certain variations thereof, it will be apparent that 20 many other changes may be made within the scope of my invention as set forth in this specification.

I claim:

1. In a fire extinguishing system of the 25 multiple solution type, a hydrant including a casing adapted to be mounted in fixed position, a separate passage through the casing for each solution, each passage being adapted to be connected to a suitable source 30 of solution supply, valve means for closing each passage, unitary means for simultaneously opening all of the passages to permit synchronous flow of the solutions therethrough, and means for connecting each 35 passage to a line of a multiple distribution system.

2. In a fire extinguishing system of the multiple solution type, separate main sources of supply each provided with an 40 outlet, a valve for closing and opening each outlet, each valve including an operating spindle, means engaging said spindles for simultaneously operating all of said valves, and means for connecting to each valve one 45 line of a multiple distribution system, the construction being such that the simultaneous operation of the valves will effect synchronous flow of the solutions into the lines of the distribution system.

50 3. In a fire extinguishing system of the multiple solution type, separate main sources of supply each provided with an outlet, a valve including a spindle adapted to be reciprocated for closing and opening 55 each outlet, means engaging said spindles and adapted to reciprocate them simultaneously to provide synchronous operation of all of said valves, and means for connecting to each valve one line of a multiple 60 distribution system, the construction being such that the simultaneous operation of the valves will effect synchronous flow of the solutions into the lines of the distribution system.

65 4. In a fire extinguishing system of the

multiple solution type, separate main sources of supply each provided with an outlet, a valve including a spindle adapted to be reciprocated to close and open each outlet, a cross head connected to all of said 70 spindles, means for reciprocating the cross head to provide simultaneous operation of all of the valves, and means for connecting to each valve one line of a multiple distribution system, the construction being such that the 75 operation of the cross head will effect synchronous flow of the solutions into the lines of the distribution system.

5. In a fire extinguishing system of the multiple solution type, separate main 80 sources of supply each provided with an outlet, a valve including a spindle adapted to be reciprocated to close and open each outlet, a cross head connected to all of said spindles, manually operated screw means for 85 reciprocating the cross head to provide simultaneous operation of all of the valves, and means for connecting to each valve one line of a multiple distribution system, the construction being such that the 90 operation of the cross head will effect synchronous flow of the solutions into the lines of the distribution system.

6. In a fire extinguishing system of the multiple solution type, separate main sources 95 of supply each provided with an outlet, a valve for closing and opening each outlet including a reciprocating spindle for operating the valve, a common housing for all of the valves, means carried by said housing 100 for simultaneously operating said valves, and means for connecting to each valve one line of a multiple distribution system, the construction being such that the simultaneous operation of the valves will effect synchronous flow of the solutions into the lines 105 of the distribution system.

7. In a fire extinguishing system of the multiple solution type, separate main sources of supply each provided with an outlet, a 110 hydrant having a plurality of chambers each connected to an outlet, a valve for closing the connection between each outlet and chamber, means for connecting to each chamber one line of a multiple distribution 115 system, and means for simultaneously operating all of the valves, the construction being such that such operation will effect synchronous flow of the solutions into the lines of the distribution system.

8. In a fire extinguishing system of the multiple solution type, separate main sources of supply each provided with an outlet, a hydrant having a plurality of chambers each connected to an outlet, a valve for closing 125 the connection between each outlet and connected chamber, each valve including an operating spindle terminating outside of said chamber, means for connecting to each chamber one line of a multiple distribution 130

system, and means engaging all of the spindles to operate simultaneously all of the valves, the construction being such that such operation will effect synchronous flow of the 5 solutions into the lines of the distribution system.

9. In a fire extinguishing system of the multiple solution type, separate main sources of supply each provided with an outlet, a 10 hydrant having a plurality of chambers each connected to an outlet, a valve for closing the connection between each outlet and connected chamber, each valve including an operating spindle passing through the chamber and terminating outside of said chamber, means for connecting to each chamber one line of a multiple distribution system, and means carried by the hydrant for engaging all of the spindles to operate simultaneously 15 all of the valves, the construction being such that such operation will effect synchronous flow of the solutions into the lines of the distribution system.

10. In a fire extinguishing system of the multiple solution type, separate main sources of supply each provided with an outlet, a 20 hydrant having a plurality of separate longitudinal chambers each connected adjacent one end with one of said outlets, a valve 25 adjacent said end for closing the outlet, a valve actuating spindle extending longitudinally of the chamber and through the other end thereof, means engaging all of the spindles outside of said chambers to operate 30 the valves simultaneously, and means for connecting to each chamber one line of a multiple distribution system, the construction being such that such operation will 35 effect synchronous flow of the solutions into 40 the lines of the distribution system.

11. In a fire extinguishing system of the multiple solution type, separate main sources

of supply each provided with an outlet, a hydrant having a plurality of separate longitudinal chambers each connected adjacent 45 one end with one of said outlets, a valve adjacent said ends for closing the outlet, a valve actuating spindle extending longitudinally of the chambers and through a bearing in the other end therein, adapted to 50 open and close the valve by reciprocating movements in said bearing, a sealing disk mounted on each spindle and adapted to bear against the bearing when the spindle is shifted outwardly to open the valve so as 55 to prevent leakage of the solution past the bearing, means engaging all of the spindles outside of said chambers to reciprocate them for simultaneous operation of the valves, the construction being such that such operation 60 will effect synchronous flow of the solutions into the lines of the distribution system.

12. In a fire extinguishing system of the multiple solution type, separate main sources of supply each provided with an outlet, a 65 hydrant having a plurality of separate longitudinal chambers each connected adjacent one end with one of said outlets, a valve seat adjacent said end of each chamber, a valve head located in each chamber and 70 adapted to engage said seat to close the outlet, a spindle engaging each head and passing through the opposite end of the chamber, adapted to open and close said outlet by reciprocating movements, means engaging 75 all of the spindles outside of said chambers to operate the valves simultaneously, and means for connecting to each chamber one line of a multiple distribution system.

Signed at New York, in the county of 80 New York and State of New York, this 30th day of December, A. D. 1919.

HAROLD I. ACKER.
